United States Patent Office.

JOHN R. RICHARDS, OF MOUNT JOY, PENNSYLVANIA, ASSIGNOR TO HIMSELF AND A. L. MENNEZ, OF SAME PLACE.

Letters Patent No. 63,305, dated March 26, 1867.

IMPROVEMENT IN SAFE-LOCKS.

The Schedule referred to in these Letters Patent and making part of the same.

TO ALL WHOM IT MAY CONCERN:

Be it known that I, JOHN R. RICHARDS, of Mount Joy, in the county of Lancaster, and State of Pennsylvania, have invented a new and useful Burglar-Proof Lock, timed by a gravitating force, to operate the same, adapted for safes and bank vaults or the like; and I do hereby declare that the following is a full and exact description thereof, reference being had to the accompanying drawings, making a part of this specification, in which—

Figure 1 is a perspective view of the duplicated sand-box A A', poised on its cylindrical axis G, and its several parts in place.

Figure 2 shows the lock-plate B removed, with its sand-boxes, &c., in order to show the combined gearing that operates the shafts to the several bolts D W.

Figure 3 is a plan view of the lock-plate B, with the sand-boxes in place, poised upon a scale-point, L, shown on the lock-plate.

Figure 4, with the pipe or hole r for the pendulum-shaft Q, opening for the socket-bolt D, and lugs m, holes n, for the feet on the rod s.

Figure 5 shows the cylindrical axis G, into which the sand-boxes open to admit the sand to pass from the upper to the lower box. H shows the headed key, with a slot, I, within the cylinder, in which it turns, and is held by a screw through the outside to rest in the collar groove on the key.

Figure 6 shows one of the bevel pinions, with its square shaft entering the square socket of a screw-bolt, W.

Figure 7 shows the head of the screw-socket square bolt D, with a box-opening, U, for the reception of the catch O, on each sand-box, as they are alternately brought in position, by turning, for refastening the socket-bolt D. F the screw, entering the socket-head D, on the shaft E of the turning-knob F.

Figure 8 is a vertical section, showing the knob-shaft, bevel-gearing, and bolt-shafts, in combination with the sand-boxes within the safe x x, and outer plate c.

The nature of this invention is to secure the door of a safe or vault permanently for a set time, in such a manner as to defy every means employed to open the same until the expiration of the allotted time, when only the knob on the outside can be turned in order to withdraw the socket and screw-bolts.

To enable others skilled in the art to make and use my invention, I will proceed to describe its construction and operation.

On a cylindrical axis, G, opposite each other, are two sand-boxes, or their equivalent, forming two sectors of a circle, say of seventy-three degrees each, marked A A'. Each may be divided, as indicated by the dotted lines on fig. 1; one opening in the slot I on the key, the other through a perforation in the same. But one chamber is deemed sufficient. On each of said boxes A there is an arm, N, at right angle to the vertical side of each box. On the end of each arm there is a cup, M, with a central opening in the bottom. The key H, entering the axis G, has a milled head or flange, J, with a mark; behind it, on the cylinder, there is a dial R, graduated, so that by turning the key more or less sand, or its equivalent, will be permitted to escape in a given time from the upper into the lower box. The rear of said central cylinder G is open, and rests upon a scale-point, L, on the plate D. The upper box being charged with its finely-sifted and lively and dry sand, or its equivalent, is drawn over and rests upon a shaft, Q, to which is suspended a freely vibrating rod or pendulum, P, and consequently the lower box is thrown upwards, so that its catch O enters the open box or slot U in the square socket-bolt D, and holds it so as to prevent it from being withdrawn by the screw on the shaft E, connected with the turning-knob F, which is operated from the outside of the door. Thus the sand continues to run, until the lower box becomes counterpoised, when, like the beam of a scale, it gravitates to a central plumb line, and the catch O is withdrawn from the square bolt-head D, and in swinging down the arm N rises upwards, and the plummet-rod or pendulum P enters the perforated bottom in the cup M, so as to allow the box to gravitate. Hence it is necessary that the safe or fixings be perfectly plumb, otherwise the plummet-rod or pendulum P will strike the bottom of the cup M and prevent the disengagement of the catch O. It therefore follows that inclining the safe in any manner or degree will not aid in dislodging the catch; even when turned upside down the sand could but run back and not help to the opening. Should the safe have been tampered with, so as to get it out of its

plumb position, it needs but to be restored, when, by turning the knob in the proper direction, not only will the square bolt D be drawn in by the screw arrangement on the turning-shaft E, but the bolts W will be unscrewed at all points at the same time, when the door readily opens; during business hours it may remain open, or the bolts screwed in or out without setting the sand-boxes. When it is desirable to close the safe, say from four o'clock p. m. to nine a. m. of next day, say for seventeen hours, the dial will indicate how far the key is to be turned; so for any amount of hours from three to thirty-six, or more.

The manner of operating the screw-bolts W, at two, four, or more points, is simply to form them with a deep square socket, into which a square rod or shaft, V, enters, and turns it in or out, accordingly as the bevel gearing $b\ 1, b\ 2, b\ 3$, fig. 8, is turned by the knob F, and the larger bevel-wheel k on its shaft E, as shown in the drawings, fig. 2 and fig. 8. A single screw-head, shaft, and bevel pinion is shown by fig. 6, and will be readily understood that by turning the screw-bolt W, by the turning of the square rod, the bolt is readily screwed into the iron casing, however thick and solid, with a thread to fit it; thus no wedge that could be introduced between the door-plate and external casing could force such a screw-bolt, made with a strong and sharp thread, and of any degree of thickness or strength. The gearing itself needs no further description, being well understood; but its application to withdrawing or inserting the screw-bolts is deemed a new feature, and in combination with the screw-socket bolt D, drawn in or pushed out by the same shaft that screws out and screws in the bolt W, makes it as novel as it is useful in application. This shaft E can neither be pushed in or drawn out itself, being prevented by a nut, z, within the door-plate e, and binding plate e, strongly secured by shoulders or otherwise, so as only to allow a rotary motion to said shaft E. And, as no key is used externally, there is nothing but the knob F and plates e visible on the outside of the door; no place for introducing powder; in short, it not only prevents burglars from opening the safe, but the owner himself, until the time has arrived, when the gravitating force, acting freely, releases the catch and allows the knob to be turned and the bolts to be withdrawn; consequently nothing is gained by the burglars in capturing the owner or person in charge, since no compulsion can be of avail, and the only alternative is to abide the time. I am aware that emergencies might arise when it would be desirable to open the safe; but fixed rules established must, in this case, be observed, which perhaps is of more importance than to open a safe at improper times. The arms N and cups M, on each box A or A', are so placed, as also the catch O, that when once charged it is only necessary to reverse the boxes in their position so as to bring the full one to the top previous to shutting the safe-door, and by inserting shaft Q of the pendulum-rod P in its pipe or place, r, in the lock-plate B, and the gauge or key set. A casing Y, fig. 8, is shown, surrounding the shaft V and screw-bolt W, and might be employed around each to cover them completely, without preventing their action. The size of the boxes and openings of the key can be readily adapted to the size of the safe, or time for closing, elected in each instance. The operation of the sand in the hour-glass is well known, and the amount discharged in a given time through a given opening easily ascertained and adjusted to particular cases.

I am aware that clock-work has been employed as an alarm on opening of locks, but I am not aware that a poised gravitating force like that of sand, mercury, or its equivalent, has ever been employed heretofore. I am also aware that racks and pinions have been used for sliding bolts in and out; but I am not aware that bolts have actually been screwed in and out, connecting the door and casing by means of a strong screw at two, four, or more points, by simply turning a knob, which at the same time draws out or pushes in a square bolt by means of a screw on its shaft, and thread in said socket.

What I claim as my invention, and desire to secure by Letters Patent, is—

1. The twin sand-boxes A A', or their equivalent gravitating force, and regulating key H, for timing the period that shall intervene before the bolt D and bolts W can be operated, so as to unlock the door by withdrawing or unscrewing them, by simply turning the knob F, substantially in the manner and for the purpose specified.

2. I also claim the socket, screw-bolts W D, operated substantially in the manner and for the purpose specified.

JOHN R. RICHARDS.
